STORAGE BATTERY CASE

Robert C. Brentrup, Bloomfield Hills, Mich., assignor to
General Motors Corporation, Detroit, Mich., a corpo-
ration of Delaware

Filed July 30, 1964, Ser. No. 81,071

Term of patent 14 years

(Cl. D26—6)

The single figure is a left end, top and front perspective view of a storage battery case, showing my new design, the rear and opposite end being substantially a mirror image thereof.

The ornamentation fragmentarily shown is continuous within the boundaries indicated.

The dominant features of my new design are shown in solid lines in the drawing.

I claim:

The ornamental design for a storage battery case, as shown and described.
